UNITED STATES PATENT OFFICE

DANIEL J. EASTHAM, OF ELDORADO, KANSAS

PUMPING APPARATUS

Application filed March 4, 1926. Serial No. 92,312.

This invention relates to pumping apparatus for oil wells and the like, and has more particular reference to an improved mechanism for effecting reciprocation of the polish rod of a well pump or the like.

The primary object of the invention is to provide a polish rod reciprocating mechanism of the above kind, by means of which the polish rod may be given a stroke of maximum length in a most desirable manner.

A further object is to provide a polish rod reciprocating mechanism of the above character which is extremely simple and durable in construction as well as efficient in operation.

In carrying out the above objects I provide a lever operatively connected to the polish rod and means for causing the lever to bodily reciprocate in a path parallel with the polish rod and to simultaneously cause said lever to swing in the same direction in which it is being bodily moved.

Still another object is to provide a polish rod reciprocating mechanism of the above kind so constructed as to be readily actuated, in plurality, from a central power plant, whereby individual sources of power are rendered unnecessary.

Further objects will become apparent as the nature of the invention is better understood, and the same consists in the novel form, combination and arrangement of parts hereinafter more fully described, shown in the accompanying drawings, and claimed.

In the drawings, wherein like reference characters indicate corresponding parts throughout the several views.

Figure 1 is a side elevational view of a polish rod actuating mechanism constructed in accordance with the present invention and in operative relation to the polish rod and casing head of an oil well pump;

Figure 2 is a top plan view of the device shown in Figure 1;

Figure 3 is a horizontal section taken substantially upon line 3—3 of Figure 1;

Figure 4 is a horizontal section taken upon line 4—4 of Figure 1;

Figure 5 is a vertical section taken upon line 5—5 of Figure 1; and

Figure 6 is a vertical section taken upon line 6—6 of Figure 1.

Referring more in detail to the drawings, 5 indicates the casing head of an oil well pump, and 6 indicates the usual polish rod which reciprocates through and projects some distance above the top of the casing head so as to be reciprocated for actuating the pump plunger, not shown. In the embodiment of the invention illustrated, there are provided

55 a pair of spaced parallel foundation beams 7 which are disposed at opposite sides of the casing head 5 and upon the surface of the ground so that said foundation beams project to one side of the casing head 5 for a greater 60 distance than to the other side thereof. A link 8 is pivoted as at 9 at its lower end to the forward end portion of each foundation beam 7, and a similar link 8^a is similarly pivoted to each beam 7 rearwardly of the casing head 5, and pivotally connected as at 10 at its lower 65 end to each of the four links 8 and 8^a is a lever

70 11. The intermediate portions of the levers 11 connected to the links 8 and 8^a of each foundation beam 7 are pivoted to the ends of a rigid bar or connecting link 12, whereby the 75 levers may swing vertically or in a plane parallel with the path of movement of the polish rod 6 while at the same time being prevented

80 from bodily moving toward or away from each other. The levers 11 are preferably formed of angularly related arms rigidly maintained in permanent angular relation by braces 13 so as to substantially constitute bell crank levers, and the upper arms of the levers 85

13 forwardly of the casing head 5 project toward the upper arms of the levers 11 arranged rearwardly of said casing head, whereby the upper ends of all of the levers 11 90 terminate in adjacent relation and adjacent to the upper end of the polish rod 6. These adjacent upper ends of the levers 11 are operatively connected to the upper end of the polish rod 6 by means of a block 14 through

95 which the polish rod projects and in which it is secured, and pairs of arms 15 suitably fastened to the sides of the block 14 and respectively projecting upwardly and pivoted to the adjacent end of the levers 11.

From the above, it will be seen that the 100

lower arms of the levers 11 and the attached links 8 and 8^a form toggle joints which, when alternately and rapidly broken outwardly or away from the casing head 5 and then 5 straightened as respectively indicated by dotted and full lines in Figure 1, will cause reciprocation of the levers 11 bodily in planes parallel with the path of movement of the polish rod 6, and at the same time cause 10 swinging movement of the levers 11 about their intermediate pivots in a plane parallel with the path of movement of the polish rod 6 whereby the latter is given a relatively long stroke in each direction with a minimum consumption of power. It will also be noted 15 that the levers 11 are swung so that their upper arms which are connected to the polish rod 6 move or swing in the same direction in which such levers are being bodily moved, 20 the upper arms of the levers 11 swinging upwardly past the links 12 when the toggle joints are straightened, and swinging past and below the links 12 as indicated by dotted 25 lines in Figure 1 when the toggle joints are broken. The specific embodiment of the invention illustrated involving the above particular arrangement of four toggle joints provides a mechanism which is well balanced and therefore efficient and durable. However, it 30 is to be understood that the invention contemplates reduction of the number of levers and toggle joints employed if found desirable, and principally resides in the provision of a lever operatively connected to the polish rod and associated with means for causing 35 the same to bodily reciprocate and simultaneously swing back and forth in a plane parallel with the polish rod.

For the purpose of breaking and straightening the toggle joints, I preferably provide 40 a pair of relatively long pitmen 16 whose forward ends are pivotally engaged with the respective pivotal connections 10 of the forward toggle joints, and a further shorter 45 pair of pitmen 17 whose forward ends are pivotally engaged with the pivotal connections 10 of the rear toggle joints, the rear ends of the pitmen 16 being pivotally connected to the upper end of a vertically swinging lever 18 which is pivotally mounted upon 50 a horizontal axis intermediate its ends and which has the rear ends of the pitmen 17 pivot- 55 ed to the lower end thereof. It is thus apparent that by connecting a power line 19 to the lever 18, the actuation of the toggle joints can be accomplished, the forward toggle joint breaking forwardly, and the rear toggle joint breaking rearwardly as shown by dotted lines 60 in Figure 1, respectively under the actuating 65 influence of the pitmen 16 and the pitmen 17. As shown, a post 20 is rigidly mounted upon 70 the rear end of each foundation beam 7 and is suitably braced relative to the latter as at 21, the lever 18 being pivotally supported 75 between the posts 20 as at 22.

As the various steps of operation have been dealt with as the detailed description progressed, it is believed that the construction and operation as well as the advantages of the present invention will be readily understood and appreciated without further detail description thereof. 70

Minor changes may be made without departing from the spirit and scope of the invention as claimed. 75

What I claim as new is:—

1. In a well pumping apparatus, a mechanism for actuating a reciprocating polished rod including a pair of opposed bell crank shaped levers each pivoted at its angle, means operatively connecting the outer end of the upper arm of each lever to said polish rod, and means for bodily moving the lever in a plane parallel with the polish rod and simultaneously swinging each lever in a similar plane and in the same direction in which the lever is being bodily moved. 80

2. In a well pumping apparatus, a mechanism for actuating a reciprocating polish rod including a pair of opposed bell crank shaped levers each pivoted at its angle, means operatively connecting the outer end of the upper arm of each lever to said polish rod, and means for bodily moving the lever in a plane parallel with the polish rod and simultaneously swinging each lever in a similar plane and in the same direction in which the lever is being bodily moved, said last named means embodying a toggle joint including the lower arm of said lever, and means for alternately breaking and straightening said toggle joint in rapid succession. 90

3. In combination with a vertically reciprocable polish rod, a base, a link pivoted at its lower end to the base at one side of the polish rod, a lever pivotally connected at its lower end to the upper end of said link, means to operatively connect the other end of said lever to the upper end of the polish rod, means to successively and alternately break and straighten the toggle joint formed by said link and the adjacent arm of said lever, and means permitting the lever to swing in a plane parallel with the polish rod and for causing the lever to reciprocate in a similar plane as the toggle joint is broken and straightened, said last named means comprising another toggle joint arranged at the opposite side of the polish rod and means connecting the intermediate portion of the lever of the last named toggle joint with the first named toggle joint lever so as to prevent relative movement of the levers toward or away from each other in directions laterally of the polish rod, and means to simultaneously break the second named toggle joint when the first named toggle joint is broken and to straighten said second named toggle joint when the first named toggle joint is straightened. 100

4. In combination with a vertically reciprocable polish rod, a base, a link pivoted at its lower end to the base at one side of the polish rod, a lever pivotally connected at its lower end to the upper end of said link, means to operatively connect the other end of said lever to the upper end of the polish rod, means to successively and alternately break and straighten the toggle joint formed by said link and the adjacent arm of said lever, and means permitting the lever to swing in a plane parallel with the polish rod and for causing the lever to reciprocate in a similar plane as the toggle joint is broken and straightened, said last named means comprising another toggle joint arranged at the opposite side of the polish rod and means connecting the intermediate portion of the lever of the last named toggle joint with the first named toggle joint lever so as to prevent relative movement of the levers toward or away from each other in directions laterally of the polish rod, and means to simultaneously break the second named toggle joint when the first named toggle joint is broken and to straighten said second named toggle joint when the first named toggle joint is straightened, said last named and first named toggle joint breaking and straightening means comprising pitmen operatively connected to the respective toggle joints and an actuating lever having said respective pitmen connected to opposite ends thereof.

In testimony whereof I affix my signature.
35 DANIEL J. EASTHAM.
